UNITED STATES PATENT OFFICE

149,713

DESIGN FOR A FRONT FOR GOGGLES

Norman H. Welvang, St. Paul, Minn.

Application July 26, 1946, Serial No. 131,954

Term of patent 3½ years

(Cl. D57—1)

To all whom it may concern:

Be it known that I, Norman H. Welvang, a citizen of the United States, residing at St. Paul, county of Ramsey, and State of Minnesota, have invented a new, original, and ornamental Design for a Front for Goggles, of which the following is a specification, reference being had to the accompanying drawing, forming part thereof.

Figure 1 is a front elevational view of a front for goggles, showing my new design;

Figure 2 is a rear elevational view of the same; and

Figure 3 is a top plan view thereof, the head band shown in broken lines being for illustrative purposes only and has been omitted from Figures 1 and 2 for convenience of illustration.

The shading in Figures 1 and 2 is for the purpose of indicating an opaque coloring on the transparent lens.

I claim:

The ornamental design for a front for goggles, as shown and described.

NORMAN H. WELVANG.
